UNITED STATES PATENT OFFICE.

JAMES A. BROGAN, OF LAWRENCE, MASSACHUSETTS, ASSIGNOR TO UNITED SHOE MACHINERY CORPORATION, OF PATERSON, NEW JERSEY, A CORPORATION OF NEW JERSEY.

STOP MECHANISM.

Application filed August 18, 1921. Serial No. 493,322.

To all whom it may concern:

Be it known that I, JAMES A. BROGAN, a citizen of the United States, residing at Lawrence, in the county of Essex and State 5 of Massachusetts, have invented certain Improvements in Stop Mechanisms, of which the following description, in connection with the accompanying drawings, is a specification, like reference characters on the drawings indicating like parts in the several 10 figures.

This invention relates to stop mechanisms, and is illustrated as embodied in a machine for winding hanks of welting or other stock. 15 In so far as there is common subject-matter, the present application is in part a continuation of my prior application Serial No. 231,205, filed April 27, 1918, upon which was granted United States Letters Patent 20 No. 1,412,837, dated April 18, 1922.

In winding hanks of welting, or other stock, which comes in lengths which are relatively short as compared to yarn or thread such as is handled by most winding and 25 reeling machines, it is important that the winding machine stop automatically when the end of each length is reached. Accordingly the present invention has for an object the provision in such a winding machine 30 of means for stopping it automatically when the end of each length of welting or other stock is reached.

With this object in view, one feature of the invention is to be found in a novel organization of a member engaging the strip 35 of stock with connections for stopping the actuating mechanism of the machine when the end of the strip runs out from under said member. As illustrated, a spring is 40 utilized to trip a lock or detent unless prevented by resistance of the stock; upon passage of the end of the strip of stock, therefore, the detent is tripped, actuating connections which throw out a clutch, thereby 45 stopping the machine.

This and other features of the invention, including specific constructions and combinations of parts, will be apparent from the following description of one embodiment of 50 my invention illustrated in the accompanying drawings, in which:

Fig. 1 is a view of the machine, partly in side elevation and partly in longitudinal section;

Fig. 2 is a partial end elevation;

Fig. 3 is a section substantially on the line 3—3 of Fig. 1;

Fig. 4 is a side elevation and Fig. 5 is an end elevation showing the detent and the slide which carries it; and

Fig. 6 is a view similar to Fig. 5 but showing a modified form of slide.

As explained in my above-identified prior application, the winding machine illustrated in the accompanying drawings comprises generally a reel 10, rotated alternately in opposite directions on shaft 12 by straps 14 operated by cranks 16 driven by shaft 18 carrying a pulley 20. The cranks, shaft, and pulley are enclosed in a casing 22. 70 Pulley 20 is rotated by a belt 24 passing over guide pulleys 26 and drive pulley 28, which supplies power to the machine.

Co-operating with reel 10 to lay the strip of welting, or other stock, in figure 8 convolutions about the arms of the reel, is a reciprocating guide throat 30, on a slide 32 which is moved by a pitman 34 actuated by a lever 36 rocked by crank 38. The welting is kept taut by a spring take-up member 40, which acts upon the welting between the guide throat 30 and a roll 42 over which the welting is passed. The operation of the foregoing parts is explained in, and covered by the claims of, my prior application, and no extended discussion is deemed necessary herein.

According to the aspect of the invention covered by the present application, pulley 28 forms one member of a clutch, carrying a pin 50 (Fig. 1), arranged to be engaged by the inner end of a pin 52 passing through a clutch disk 54. Disk 54 is loosely mounted on the hub of an axially-movable power-driven pulley 56, to which it is secured by a spring 58. Thus when pulley 56 is moved axially to a position where pin 52 engages pin 50, power is yieldingly transmitted from pulley 56 through spring 58 to clutch disk 54, and thence by means of pins 50 and 52 to pulley 28 which drives the machine. This prevents jars in starting the operation of the machine. To prevent undue tension of spring 58, pin 52 extends through disk 54 and the outer end of said pin projects between two spokes of pulley 56, which engage it if there is too great relative angular movement of disk 54 with respect to pulley 56.

Pulley 56 is rotatably mounted on a slide rod 60 passing through bearing 62 about 110

which pulley 28 rotates, the pulley 56 being restrained as shown from sliding movement on the rod. The opposite end of rod 60 is flattened (Fig. 4), and carries a pin 64 running in a cam slot 66 (Fig. 3) in disk 68, which is turned to reciprocate rod 60 to stop and start the machine.

Disk 68 is mounted on a rock shaft 70, arranged to be turned by lever 72 having a pin 10 and slot connection with a slide 74, which is formed with slots 76 engaging pins 78 on a stationary support 80 carried by casing 22. By this arrangement, vertical reciprocation of slide 74 acts through the above-described 15 mechanism to stop and start the machine.

In order that the position of slide 74 may be controlled automatically by the work, a 20 detent or lock member 82 is pivotally mounted on slide 74, to engage a lug 84 on support 80 when the slide is in its uppermost position. When a strip of stock is in the machine, one side of it engages a roller 86 on support 80 (Fig. 1), and the other side is 25 engaged by a roller 88 carried by one arm of detent 82 and arranged to guide the strip. The rollers 86 and 88 are further arranged so that the detent can not be tripped to clear lug 84 until the passing of the end of the strip from between the two rollers allows 30 roller 88 to be rocked toward roller 86 by spring 90 carried by lug 92 on detent 82, and engaging support 80. When this does take place, however, slide 74 drops and the above-described stop mechanism is actuated.

35 In order that slide 74 may be raised to start the machine when a fresh strip of weltting or other stock has been supplied, detent 82 is carried on a handle 94, by which it may be moved laterally, against the resistance of 40 spring 96, to clear lug 84.

According to the modification shown in Fig. 6, the stop mechanism may be thrown out to allow the machine to operate continuously if desired, by turning handle 98 to 45 bring hook 100 into supporting engagement with a pin 102 carried by support 80.

While my invention has been described as embodied in a welt-winding machine such as is claimed in my prior application, it is 50 not the intention to limit its scope thereby, or otherwise than by the terms of the appended claims.

Having described my invention, what I 55 claim as new and desire to secure by Letters Patent of the United States is:

1. A winding machine comprising, in combination, a winding reel, driving mechanism therefor, stop mechanism for said driving mechanism, and controlling means for said 60 stop mechanism comprising a pair of tension members yieldingly engaging with opposite sides of a strip of stock being wound on the reel, one of said members being arranged to guide the strip, and connections between said 65 member and the driving mechanism to ren-

der the latter inoperative when a relative movement of the two members toward one another is permitted by passage of the strip from between the members.

2. A winding machine comprising, in combination, a winding reel, mechanism for actuating the reel, stop mechanism for said driving mechanism, and controlling means for said stop mechanism comprising a pair of rolls adapted yieldingly to engage a strip of stock between them, one of the rolls being arranged to guide the strip, and connections between said roll and the actuating mechanism to render the latter inoperative when said roll is permitted to move toward the co-operating roll owing to the absence of the strip between the rolls.

3. A winding machine comprising, in combination, a winding reel, mechanism for actuating the reel including a driving clutch, a clutch operating slide, connections between the slide and the driving clutch, a control device for said slide comprising a pivotally mounted member yieldingly engaging with a strip of stock being wound on the reel and adapted to prevent movement of the slide to disengage the clutch, and a spring for actuating said member when the stock is removed from engagement therewith to release the slide.

4. A winding machine comprising, in combination, a reel, mechanism for actuating the reel including a clutch, a slide, connections between the slide and the clutch adapted to disengage the clutch when the slide is moved in one direction, a control member for said connections arranged to be engaged by a strip of stock being wound on the reel and adapted to prevent movement of the slide into a clutch-disengaging position, and means tending to move said member to enable the slide to move into clutch disengaging position when the stock is removed from engagement with said member.

5. A winding machine comprising, in combination, a reel, mechanism for actuating the reel including a clutch, a slide, connections between the slide and the clutch, a tripping lever pivoted upon the slide and engaged at one end with a strip of stock being wound on the reel, and means for normally moving the lever to permit the slide to move into a clutch disengaging position when the stock is removed from engagement with the lever.

6. A winding machine comprising, in combination, a reel, a rotary shaft to drive the reel, a clutch governing the application of power to the shaft, stop mechanism for throwing out the clutch, a pair of tension rollers yieldably engaging with opposite sides of a strip of stock to be wound upon the reel, and a detent carrying one of the tension rollers adapted normally to hold

the stop mechanism inoperative and to be tripped upon the removal of the strip from between said rollers.

7. A machine for operating on a strip of stock comprising, in combination, a clutch, a member to open and close the clutch, a rock shaft to actuate said member, and a device to engage the stock to maintain the shaft in one position to close the clutch as long as stock is supplied and to rock it to another position to open the clutch when released by passage of the end of the strip of stock.

8. A machine for operating on a strip of stock comprising, in combination, instrumentalities to operate on the stock, a two part clutch one member of which delivers power to operate said instrumentalities, a power-driven pulley connected to transmit power yieldingly to the other member of the clutch so that the machine may be started without a jar, and work controlled means to open and close the clutch.

9. A machine for operating on a strip of stock comprising, in combination, stopping and starting mechanism, a slide whose position controls said mechanism, a fixed lug, a detent carried by the slide and arranged to engage the lug to hold the slide in operating position and having a portion to engage the strip of stock to hold the detent in operative position, and a spring to trip the detent when permitted by the stock.

10. A machine for operating on a strip of stock comprising, in combination, stopping and starting mechanism, a slide the position of which controls said mechanism, a fixed lug, a detent pivotally mounted upon the slide and arranged to be tripped by a swinging movement about its pivotal axis and also to be manually disengaged from said lug by movement in the direction of said axis, said detent having a portion to engage the strip of stock to hold the detent in operative position, and a spring to trip the detent when permitted by the stock.

11. In a winding machine, a reel, means for actuating the reel including a clutch having an axially movable driving clutch member, a rock shaft, connections between said rock shaft and the driving clutch member for actuating the latter to render the clutch active or inactive, a slide, connections between said slide and rock-shaft for operating the latter, a fixed lug, a detent carried by the slide and arranged to engage the lug to hold the slide in operating position, means engaged by the stock being wound for holding said detent in engagement with said lug, and a spring to trip the detent when the stock becomes exhausted.

In testimony whereof I have signed my name to this specification.

JAMES A. BROGAN.
